AIRPLANE

Francis E. Schier, Oregon, III.

Application January 19, 1951, Serial No. 13,872

Term of patent 7 years

(Cl. D71—1)

To all whom it may concern:

Be it known that I, Francis E. Schier, a citizen of the United States, residing at Oregon, in the county of Ogle and State of Illinois, have invented a new, original, and ornamental Design for an Airplane, of which the following is a specification, reference being had to the accompanying drawing, forming part thereof.

Figure 1 is a top plan view of an airplane, showing my new design;

Figure 2 is a side elevational view thereof, and Figure 3 is a front end view of the same.

I claim:

The ornamental design for an airplane, as shown.

FRANCIS E. SCHIER.
